COMBINED BUMPER AND LAMP UNIT FOR AN AUTOMOBILE

William M. Brownlie, Dearborn, Mich., assignor to Chrysler Corporation, Highland Park, Mich., a corporation of Delaware

Application July 17, 1959, Serial No. 56,826

Term of patent 7 years

(Cl. D14—6)

Fig. 1 is a front view of a combined bumper and lamp unit for an automobile embodying my new design;

Fig. 2 is a top plan view thereof;

Fig. 3 is a side elevational view thereof;

Figs. 4, 5 and 6 are sectional views taken on the lines 4—4, 5—5 and 6—6, respectively, of Fig. 1; and

Fig. 7 is a sectional view taken on the line 7—7 of Fig. 2.

The dominant features of my design reside in the full line portions of the drawings.

I claim:

The ornamental design for a combined bumper and lamp unit for an automobile, substantially as shown and described.
